WASTE PAPER PRESS

Bengt A. F. Andersson, 11 Gyllensvardsgatan,
S-302 34 Halmstad, Sweden

Filed Jan. 28, 1975, Ser. No. 544,696

Term of patent 14 years

Int. Cl. D15—99

U.S. Cl. D55—1 B

FIG. 1

FIG.2

FIG. 3

FIG. 4

FIG. 1 is one side view of a waste paper press embodying my new design;
FIG. 2 is the other side view thereof;
FIG. 3 is a front view thereof; and
FIG. 4 is a plan view thereof.
I claim:
The ornamental design for a waste paper press, substantially as shown and described.
